The ornamental design for a stake for attachment to drip or related irrigation tubing, as shown and described.

DESCRIPTION

FIG. 1 is a front elevational view of a stake for attachment to drip or related irrigation tubing showing my new design;

FIG. 2 is a right side elevational view thereof, the left side being a mirror image thereof;

FIG. 3 is a rear elevational view thereof;

FIG. 4 is a top plan view thereof; and,

FIG. 5 is a bottom plan view thereof.
